UNITED STATES PATENT OFFICE.

ALFRED STERNER, OF CHICAGO, ILLINOIS.

BOILER-TUBE-SCALE REMOVER.

Application filed July 26, 1920. Serial No. 398,960.

To all whom it may concern:

Be it known that I, ALFRED STERNER, a citizen of the United States, residing at Chicago, in the county of Cook and State of Illinois, have invented certain new and useful Improvements in Boiler-Tube-Scale Removers, of which the following is a specification.

My invention relates to a device for removing the scale from boiler tubes and is especially adapted to be used in locomotive boilers where it is inserted either in the water tubes of the boiler so as to remove the scale formed inside of said tubes, or into the fire tubes and remove the scale formed on the outside of the fire tubes, and by the use of compressed air or other fluid imparting to the boiler tubes a succession of light blows whereby the scale is removed therefrom.

It is well known that heretofore in removing the scale which forms on the outside of the fire tubes of a locomotive boiler the only feasible means was to gain access to the tubes through the boiler shell from outside the shell and by the use of hammers knock the scale off the tubes.

My improved device is adapted to be inserted into and to be passed through the fire tubes, and by a succession of blows jar the scale loose from the outside of the tubes so that it can be washed out of the boiler and at the same time loosen the scale and dirt in the inside of said tubes so that it can be removed by the use of compressed air or any other suitable means.

For the removal of scale from water tube boilers I provide smooth faced head members which are adapted to exert a slight hammer blow upon the inside of the tubes and for the removal of scale from water tubes these members have corrugated or ribbed surfaces so that the scale is cut loose from the inside of the tube as well as knocked loose by the hammer blow.

Another and further object of my invention is the provision of water tube cleaning means whereby a succession of light blows is directed against either a water tube or a fire tube in a steam boiler without danger of loosening up the joints of the tubes between the flue sheet and the boiler tubes.

Another and further object of my invention is the provision of a boiler tube cleaning device which is portable, easily handled

and which will be simple and efficient in operation.

These and other objects of my invention will be more readily and better understood by reference to the accompanying sheet of drawings, and in which—

Figure 1 is a longitudinal sectional view of my improved invention showing the hammer in full lines in its forward position and in dotted lines in its rearward position;

Figure 2 is a view in elevation of the forward end of my improved invention showing the type of head members illustrated in Figure 4.

Figure 3 is a sectional view on line 3—3 of Figure 1;

Figure 4 is a view in elevation of one type of head member having transversely extending ribs or corrugations on the outside surface thereof for removing scales from water tube boilers;

Figure 5 is a view in elevation of a head member having a slightly different form of corrugation; and

Figure 6 is a view in elevation of one of the head members having a smooth surface and adapted to be used in the fire tubes of steam boilers for removing the scale from the outside of said tubes.

Referring specifically to the drawings and in which like reference characters refer to like parts throughout, 10 is a cylinder having a cap 11 in threaded engagement with the rear end of said cylinder and which serves to close the rear end of the said cylinder and having passages therein through which compressed air is admitted to said cylinder as hereafter described. The cylinder 10 has an enlarged annular chamber 12 centrally located thereof and a chamber 13 in the rear portion of said cylinder of slightly less diameter than the chamber 12 and an opening 14 forward of said chamber 12 of slightly less diameter than the chamber 13 and in which the piston hereinafter described operates. Slidably mounted within the said cylinder 10 is a piston 15 having a slightly enlarged rear portion 16 of substantially the same diameter as the chamber 13 within which the rear end of the piston 15 operates. An annular channel 17 extends around the piston 15 just forward of the enlarged portion 16 so that an annular shoulder 18 is formed upon the said piston 15 for the purposes hereinafter described.

100
105
110

Extending longitudinally of the said piston 15 for approximately three-fourths of its length is a passage 19 open at its rear end and communicating near its forward end with a pair of transversely extending passageways or ports 20 and 21 in said piston, the said passageways extending entirely through the said piston 15. The forward end of the said cylinder 10 is slightly enlarged and has a plurality of wedge shaped prongs 22, 23, 24 and 25 extending forwardly of said cylinder 10 and integral therewith, the wall of the cylinder 10 being cut away between each pair of the prongs 22, 23, 24 and 25, so as to provide a triangular space for the reception of the head members or hammers 26, 26, four of which are provided, one of said members being particularly illustrated in Figure 4. The members 26 have a wedge shaped body portion 27 and laterally extending projecting portions 28 and 28^a integral with the body portion 27, and extending beyond any one pair of the prongs 22, 23, 24 and 25, the said portions 28 and 28^a together with the outer end of the body portion 27 forming almost a complete circle so that the head members 26 come into contact with the entire inner surface of the boiler tubes. The members 27 are slightly curved at their forward ends as at 29, to allow for easy insertion of the device into a boiler tube and also in order that the device can more readily be passed through curved tubes. Ribs 31^a extend transversely across the members 26 so as to cut the scale from the outer tubes of boilers more readily. Extending transversely across the body portion 27 of the head members 26 is a recess 30 and into which a spring 31 is seated so as to hold the members 26 securely in position at the forward end of the cylinder 10 between the prongs or members 22, 23, 24 and 25 which have a recess 32 extending transversely across and into which the spring 31 is seated upon the members 22, 23, 24 and 25 so that the head members 26 are held in position with a considerable freedom of movement. The forward end 33 of the piston 15 is pointed so that as it reciprocates in the manner hereinafter described it passes between each of the members 26, it will render a succession of blows against the inner edges of the members 26 which jars loose the scale on the boiler tubes. The end 33 of the piston 15 being pointed the force of the blow will be extended upon the members 26 gradually, but will be enough to be effective. The sides of the members 26 are in contact with the side of the prong members heretofore described and completely fill up the space between the members. The inner edges 34 of the members 26 are slightly curved so that as they ride upon the front end 33 of the piston 15 there is a rocking motion of

the members 26 so that they will conform to the curves in the boiler tube and also enable the device to be more easily inserted into a boiler tube. The head portion 28 of the members 26 is triangular in shape and forms a segment of a circle with a slight space between each of the members 26 forwardly of the prongs 22, 23, 24 and 25 so that as illustrated in Figure 2 the device forms substantially a complete circle. 75

The cap 11 has a well portion 35 and a rearwardly extending tube portion 36 and a ball end 37 thereon over which an air hose 38 is passed which grips the portions 36 and also the portion 37 of the member 11. A split bushing 39 is provided which is in threaded engagement with the member 11 and serves to hold the hose 38 securely upon the member 36 and prevent the compressed air from escaping between the bushing and the portion 36 of the member 11. The member 36 and ball end 37 have a passage 40 extending longitudinally thereof and into the member 11 where it joins a plurality of transversely extending passages 41 in the end cap 11. The cap 11 has an inwardly projecting portion 42 which abuts against the rear end of the cylinder 10, the said portion 42 extending inwardly a short distance beyond the marginal edge 95 of the cap 11 so that an annular space 43 is formed between the cap 11 and the cylinder 10. Communicating with the annular space 43 and located in the walls of the cylinder 10 in its rear portion thereof is a plurality of longitudinally extending passages 44 which communicate with the enlarged annular chamber 12 in said cylinder and through which compressed air is admitted to the cylinder 12 as hereinafter described. 100 The rear end of the piston 15 is slightly cupped shaped as at 45, so that when the piston 15 is against the portion 42 of the member 11 compressed air can be admitted behind the piston and will serve to force 110 the piston forward.

Illustrated in Figure 5 is a slightly different form of head member comprising a body portion 46 having a transversely extending recess 47 and laterally extending 115 projecting portions 48 and 48^a. These members are exactly the same form and contour as the members 26 heretofore described, except that their outer surfaces are corrugated instead of ribbed, and in Figure 6 is illustrated another member of the same size and contour as the members 26 having a body portion 49, a transversely extending recess 50 and laterally extending head portions 51 and 51^a, the entire outer surface of the 120 said member 49 being smooth and adapted to be used upon fire tubes for loosening and knocking off the scale formed upon the outside of the said tubes. 125

In the operation of the device the hose 38 130

leads to any suitable supply of compressed air which is admitted to the cylinder 10 through the passage 40 in the member 36 and through the passages 41, 41, to the annular space 42 and forwardly through the passages 44 into the enlarged chamber 12 of the cylinder 10. Thereupon the air catching against the annular shoulder 18 on the piston 15 forces the piston 15 rearwardly in the cylinder, the head portion 33 is withdrawn from between the hammer members 26 and backward until the transversely extending passages 20 through the piston 15 is uncovered and into communication with the enlarged chamber 12, whereupon the compressed air will enter through the passage 20 and pass rearwardly through the passage 19 and into the chamber 13 in the rear portion of the cylinder and drive the piston 15 forward with a resulting blow upon the hammer members 26 as the forward pointed end 33 of the piston comes into contact with the curved surfaces 34 of the members 26. As the piston 15 passes forward the passage 20 passes into the chamber 14 of the cylinder 10 so that the supply of air is cut off and immediately thereafter the passage or port 21 passes outward through the chamber 14 and between the prong members 22, 23, 24 and 25 so that the port 21 is uncovered and the compressed air escapes from the chamber 13 out through the passages 19 and 21 until the air is at atmospheric pressure or substantially so. Thereupon the compressed air by exerting its force against the shoulder 18 drives the piston rearwardly again and as long as the supply of air is continued to the cylinder 10 the piston 15 will be reciprocated back and forth in the cylinder 10 and each time it is thrown forward will exert a light blow upon the hammers or members 26, thus loosening the scale inside of the boiler tubes, and also outside thereof, and if used upon water tubes will loosen the scale in the said water tubes so that it can be washed out.

While I have described more or less precisely the details of construction, I do not wish to be understood as limiting myself thereto, as I contemplate changes in form and the proportion of parts and the substitution of equivalents as circumstances may suggest or render expedient, without departing from the spirit or scope of my invention.

I claim:

1. A flue cleaner, comprising a cylinder, a reciprocating piston therein, having a forward pointed end, means to supply an operative agent to said piston, hammer members carried by said cylinder having arcuate inner faces adapted to rock upon the forward end of said piston, and spring means intermediate the ends of said hammers and bearing against the same for holding them in contact with the piston. 60

2. A flue cleaner, comprising a cylinder, a reciprocating piston therein having a forward pointed end, means to supply an operative agent to said piston, loosely mounted hammer members carried by said cylinder at the forward end thereof and held in rocking engagement with the forward pointed end of the said piston when the 75 said piston is in its forward position in said cylinder, and spring means intermediate the ends of said hammers bearing against the same for holding them in contact with the piston. 80

3. A flue cleaner, comprising a cylinder, a reciprocating piston therein having a forward pointed end, means to supply an operative agent to said piston, hammer members carried by the said cylinder, a closure member for said cylinder having a hollow outstanding portion integral therewith, the said portion having an enlarged part at the end thereof over which a flexible pipe extends, a gland in threaded engagement with 90 said closure member, and spring means intermediate the ends of said hammers bearing against the same and holding them in contact with the piston. 85

4. A flue cleaner, comprising a cylinder 95 having a plurality of circumferentially positioned openings in the forward end thereof, a plurality of loosely mounted, radially movable hammer members positioned in said openings, means to retain the said hammer 100 members in position in said cylinder, a reciprocating piston mounted in said cylinder having a forward pointed end, and means to supply an operative fluid agent to said cylinder, the inner faces of the said hammer 105 members being arcuate shaped and adapted for rocking engagement with the forward pointed end of the said piston.

Signed at Chicago, Illinois, this 21st day of July, 1920.

ALFRED STERNER.
